GARMENT STRETCHER AND CREAMER

Walter C. Hansen, St. Louis, Mo.

Application October 6, 1938, Serial No. 233,512

6 Claims. (CL. 287—58)

This invention relates to garment stretchers and creasers, and with regard to certain more specific features, to adjustable apparatus of this class for placement within garments.

Among the several objects of the invention may be noted the provision of a light-weight stretcher and creaser which is readily adaptable in its functions to various forms and sizes of clothing; the provision of apparatus of the class described which is adjustable and which may be retained inside the garments while the latter are being stored, or dried, or the like; and the provision of apparatus of this class which is economical to manufacture and which may be operated with facility. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawing, in which is illustrated one of various possible embodiments of the invention,

Fig. 1 is a plan view of my stretcher and creaser set to its small dimensions;

Fig. 2 is a view similar to Fig. 1 but showing the device in the leg of a pair of trousers and expanded in form to larger dimensions for stretching and creasing;

Fig. 3 is a cross section taken on line 3—3 of Fig. 2;

Fig. 4 is a cross section taken on line 4—4 of Fig. 2; and,

Fig. 5 is a fragmentary perspective view showing details of a locking mechanism.

Similar reference characters indicate corresponding parts throughout the several views of the drawing.

Referring now more particularly to Fig. 1, there are shown at numerals 1 and 3 separate side strip members of thin rectangular cross section (see Fig. 5). Member 1 is formed with endwise and laterally directed, parallel parts 5 and 7 at corners 9; and the member 3 is formed with endwise and laterally directed, parallel parts 11 and 13 at corners 15. The rounded nature of the corner portions (such as 9) is indicated in Fig. 5. Parts 1, 5 and 7 form a U-shaped member A and parts 3, 11, 13 form another U-shaped member B. The open mouths of the U-shapes are directed towards one another with the laterally directed portions 5, 7 and 11, 13 lying adjacent one another respectively, and being relatively

slidable. The ends of the sliding portions 5 and 11, 7 and 13 are bent over or deformed to provide offset lugs 17.

Surrounding the pairs of end members 5 and 11, or 7 and 13, as the case may be, is a pair of sliding preferably tubular, thimbles 19. The opening 21 through each thimble is of a rectangular cross section or dimension which is just large enough slidably to accommodate the pairs of end members surrounded, when the thimbles 19 are in mid-position, such as shown in Fig. 1. In this more or less central position of the thimbles 19, the end members 5, 11 as well as the end members 7, 13, are relatively slidable so as to provide a lateral adjustment in the U-shapes A and B. The said dimension is less than the maximum distance between the opposite exterior surfaces of the end members. When a desired adjustment has been attained, the thimbles 19 are pushed laterally, whereupon they ride over and squeeze the sloping portions 23. The sloping portions or cam surfaces 23 are caused by the supporting action of the lugs 17. The portions 23 are preferably not bent into sloping condition but merely spring into position. Bending is at 17, hence they provide springing and frictional holding means for the thimbles 19. The thimbles 19 being located between the end members 17 are held captive and are prevented from moving over the end of either section or member 5, 7, 11 or 13.

The cross-sections of the members 1, 5, 7; and 3, 11, 13 are rectangular and relatively thin so as to provide a lateral flexibility but relative stiffness in the plane of the quadrilateral formed by the parts as shown. Thus, although the device as a whole is relatively stiff in its quadrilateral plane, the sloping portions 23, being more or less flexible, provide a springing means by which the thimbles 19 are retained in their laterally pushed positions so that the respective arms 5, 11 and 7, 13 are frictionally held in predetermined positions after adjustment.

The operation of the device is as follows:

It is brought into the position shown in Fig. 1 wherein the thimbles 19 are more or less centrally located. In this condition, the lower and smaller end of the resulting quadrilateral may be inserted through the waistband of a pair of trousers, for example, and into one leg. When properly positioned within the trousers, the U-shaped members A and B may be pushed apart at each of their ends, thus extending the breadth of the device so that it stretches and tensions the trouser legs and acts as a creaser where the cloth is bent over the relatively thin rectangular

sections 1 and 3. After extension, the thimbles 19 are pushed laterally, so that they engage portions 23 to frictionally hold the relationship of parts shown in Figs. 2-5. Inverse operation of the device serves to provide for removal.

In extended position, the device has the function of maintaining the cloth of the trousers or the like in tension, thus preventing the introduction of wrinkles, as when drying, or when stored. At the same time, a pre-formed crease is maintained, or a crease is introduced, particularly in damp cloth which is drying while stretched.

Advantages of the device are:

15. 1. Its edges are thin, and hence a creasing function is performed by the members 1 and 3 at the same time that stretching is effected.

20. 2. It is extremely simple to manufacture. For example, in manufacturing the device, it is only necessary to bend two flat metal strips and to turn over the end portions as at 17. The thimbles are very simple to press into form and position.

25. 3. It is light in weight and takes up very little room.

4. It is simple to operate.

It will be understood that one device such as shown in Fig. 1 is inserted into each trouser leg. It is also clear that suitable hooks may be used 30 for support if it is desired to hang the trousers for storage. Otherwise, they may be stored by laying them out flat with the stretchers therein. The flatwise arrangement of the bars facilitates the storage of many in stacks, as well as favoring 35 the formation or preservation of a crease.

The principles of construction are applicable to forms of the device for other elements of clothing such as sleeves, shirts, etc.

40. Advantages of the invention are due to the following conditions:

(1) That the adjacent portions such as 5 and 11 are flat, which prevents them from slipping past one another when compressed by the annulus or thimble member 19. This is regardless 45 of whether this annulus is long or short. Thus, these portions frictionally engage over an extensive length.

(2) The advantageous elongated form of thimble member 19 ensures an improved frictional grip directly between the adjacent members such as 5 and 11, regardless of the shape of 50 said members.

The combination of the elongate thimble and flat portions is particularly effective, although 55 each without the other, comprises a substantial advantage.

In view of the above, it will be seen that the several objects of the invention are achieved and other advantageous results attained.

60. As many changes could be made in the above constructions without departing from the scope of the invention, it is intended that all matter contained in the above description or shown in the accompanying drawing shall be interpreted as illustrative and not in a limiting sense.

I claim:

1. An adjustable joint for clothing stretcher bars and the like, comprising a pair of adjacent, relatively slidable sections, an integral portion of at least one of said sections being directed 70 toward the other section to provide a resilient wedge-shaped portion between sections, and at least one separate sliding tubular thimble snugly

surrounding the sections where the sections are closely adjacent to one another, said thimble being adapted to slide over said wedge-shaped portion to effect a frictional grip between the sections.

2. An adjustable joint for clothing stretcher bars and the like comprising a pair of adjacent, substantially parallel, relatively flat sections, composed of deformable material and being relatively slidable along their flatwise sides, an integral portion of each one of said sections being deformed respectively in a direction toward the other section to provide resilient wedge-shaped portions between sections, and sliding thimbles surrounding the sections and adapted 15 to slide over said wedge-shaped portions to effect a squeezing frictional grip, each of said thimbles being prevented from moving over the end of either section.

3. An adjustable joint for clothing stretcher bars and the like comprising a pair of adjacent, substantially parallel, relatively flat sections which are relatively slidable on their flatwise sides, end means on each one of said sections directed respectively toward the other section to provide resilient wedge-shaped portions between sections, and sliding thimbles surrounding the sections and located between said end means and adapted to slide away from one another over said wedge-shaped portions to effect 30 a frictional grip and being held captive against endwise escape by said end means.

4. An adjustable joint for clothing stretcher bars and the like, comprising a pair of relatively flat slidable sections having adjacent portions, means on one of said sections arranged to maintain said sections in spaced relation to each other at a neighboring region, a separate slid- 40 able annulus closely surrounding the said sections at their adjacent portions, said annulus having an interior dimension less than the maximum distance between the opposite exterior surfaces of said sections at the spaced regions thereof, and said annulus being arranged to slide over said adjacent portions and onto the spaced regions of said sections to frictionally 45 grip the sections together with the annulus.

5. An adjustable joint for clothing stretcher bars and the like, comprising a pair of adjacent relatively flat slidable sections, an integral portion of at least one of the sections being directed 50 away from the other section to provide a sloping cam surface, and at least one separate sliding annulus closely surrounding said sections where the sections are closely adjacent one another, said annulus being adapted to slide onto said sloping cam surface to effect a frictional grip 55 between the sections.

6. An adjustable joint for clothing stretcher bars and the like, comprising, a pair of relatively 60 slidable resilient metal sections having flat surface portions in close adjacency, a portion of one of said sections being bent out of alignment with said closely adjacent portions to provide a region whereat the sections are spaced from each other; a separate slide closely embracing said sections at their adjacent portions and arranged to be moved onto said spaced region, the internal dimension of said slide being less than the maximum distance between opposite exterior surfaces of said portions at the spaced 70 region.

WALTER C. HANSEN.
